UNITED STATES PATENT OFFICE

CHARLES W. GREEN, OF ILION, NEW YORK, ASSIGNOR TO REMINGTON ARMS COMPANY,
INC., A CORPORATION OF DELAWARE

CASH REGISTER

Original application filed October 20, 1925, Serial No. 63,695. Divided and this application filed June 14, 1927. Serial No. 198,842.

This invention relates to improvements in cash registers and more particularly to that type employing a plurality of individual totalizers for segregating the entries according to their class.

6 This application is a division of the pending application of Charles W. Green, Ser. No. 63,695, filed October 20, 1925, to which reference may be had for a more complete description of the cash register to which 10 the present invention has been applied. While the improvements set forth in this application are shown applied to a particular type of cash register illustrated in the parent application their utility is by no means 15 limited to this specific embodiment. The improvements are of such a nature that they may be applied in various modifications to many other kinds and principles of cash 20 registers and accounting machines.

25 The principal object of this invention is to provide a plurality of individual totalizers for keeping separately the amounts of the receipts of different clerks, departments of a store, or the different transactions that occur in a mercantile establishment.

30 The main object is to provide an improved type of totalizer selecting mechanism so that by a preliminary adjustment there may be established a co-operative relation between any one of said totalizers and a common totalizer operating means.

35 A further object is to provide improved devices for throwing the totalizers out of operative relation when certain special keys, such as, "Paid out", "Charge" or similar keys are operated.

40 In the preferred embodiment of the invention as disclosed in the drawings, the improvement which is effected by the present invention is the simplification of the mechanism usually utilized for controlling the engagement of one of a plurality of totalizers. Machines of the general type to which the

45 present invention has been applied are usually provided with connections from the main operating shaft for causing the engagement with the actuators of the totalizer of a single totalizing mechanism, or of a selected totalizer of a machine equipped with more than

one totalizer. In machines of the latter type, the engaging mechanism is frequently not only designed to select the totalizer in which it is desired to insert the entry of a particular item, but it is usually provided with additional means under control of certain special keys, such as, "Charge" and "Paid out" keys of a cash register, so that an item may be prevented from being entered into any of the totalizers. This function of preventing the engagement with the actuators of a totalizer which has been selected, is known as a "throwout" function. According to the present invention the totalizer engaging mechanism is adapted both to select one of a plurality of totalizers for engagement with the actuators and to cause a throwout function of the selected totalizer upon the operation of a special key.

50 In accomplishing this result a great simplification has been introduced by the present invention through the use of a single shifttable and pivoted slide for both selecting a totalizer and providing the throwout function. The slide is normally adapted to be rocked, upon an operation of the machine, about a pivot at one end, and when so rocked it will normally cause the engagement of one of the totalizers. Operation of a totalizer selecting element, such as a clerk's key, is designed to shift the slide by moving its pivotal point so that, during the subsequent operation of the machine, the first totalizer will not be affected but another totalizer will be 55 rocked into engagement with the actuators. Still further movement of the slide by shifting the pivotal point still further by connections from a special manipulative means, such as a "Paid out" or "Charge" key, will serve to completely disengage the slide from the operating mechanism. Thus, when the slide is in this position, none of a plurality of totalizers will be engaged with the actuators.

60 In order that a totalizer which is not intended for operation will not be accidentally rocked, a special detent element is placed under control of the selecting slide and this element will prevent the movement of one or another of the totalizers. Suitable means is

similarly provided to prevent the rocking of any totalizer when a "throwout" key has been operated.

In carrying out the present invention it 5 has been found an advantageous feature to employ a single train of connections from all of the controlling keys to the single controlling slide. These connections may include a rock shaft extending across the 10 clerk's and special transaction keys, so that a cam shoe may be pinned to the shaft, adjacent any of the desired keys, in order that pins carried by such keys may rock the shaft to different extents to either select a totalizer 15 or perform a throwout function. By applying the principle of the totalizer control mechanism, disclosed herein, the system of selection and elimination of totalizers for engagement with the actuators may be very 20 readily varied, so that if desired, two totalizers may be engaged at one time with the actuators, and one may be eliminated without eliminating the other, or both may be eliminated simultaneously.

25 Reference will now be had to the figures of the drawings, which, taken in connection with the detailed description which will follow, constitute a full disclosure of one form of the invention.

30 In the drawings:

Fig. 1 is a sectional view in elevation of the machine which is used for the purpose of illustration showing particularly the operating keys, the differential mechanism and 35 the mechanism for controlling the engagement of the totalizers, together with the connections from the special keys for controlling the selection of the totalizers.

Fig. 2 is a detail view of one of the 40 elements of the totalizer engaging and selecting devices which is utilized for the purpose of locking the undesired totalizers in their normal positions.

Fig. 3 is a plan view of the machine showing 45 the arrangement of the multiple totalizers, the totalizing engaging mechanism and their connections to the special keys for controlling the selection or disengagement of the totalizers.

50 The general construction and operation of the various features of the invention, as embodied in the illustrative machine, have been explained rather fully in the foregoing statement of the objects of the invention. A 55 detailed description will now be given of the essential elements of the machine embodying the invention defined by the appended claims.

50 The machine which is used for the purpose of illustration is of the key operated type of cash register and is provided with the usual series of operating keys, including amount keys 20 and a number of special keys which will be later described.

65 The machine, as disclosed, is provided

with a plurality of banks of amount keys but obviously the capacity of the machine and the designation of the amounts may be varied to suit the particular use to which the invention is put. The operating keys, as 70 shown in Fig. 1, are all mounted on a transverse shaft 21 and the keys are normally maintained with their forward operating ends elevated by means of a weighted bail 22 extending across the tops of all the keys in 75 rear of their pivots, the bail having a plurality of arms extending forwardly and pivoted about the key shaft 20. Depression of the forward end of any key will serve to elevate the weighted bail 22 and carry the 80 upper surface of the latter substantially into engagement with the under cut-out surface of a key coupler 23. At the same time, an upper surface 24 toward the rear end of the key will engage the under surface of a projecting lip 25 of the key coupler. Continued depression of the forward end of the key will 85 then serve to elevate the key coupler 23 as well as the bail 22 and during this continued movement of the parts the lip 25 of the coupler will enter the notch 26 of the operated key.

90 The usual connections are provided from the key coupler to a main operating shaft 95 within the machine, these connections comprising a double rack member 27 (Fig. 1) having sets of oppositely facing rack teeth adapted to alternately engage a pinion 28 (Fig. 3) mounted on a main operating shaft 29. As is well known in the art, the oscillation of the key coupler by the depression and return of one or more of the operating keys 100 will serve to produce a full rotation of the shaft 29.

105 Adjacent to each of the amount keys and pivoted upon the key supporting shaft 21 is a cam plate 30 which is provided with an operating cam slot 31, the slots of the cam plates of a series being graduated to effect an action 110 of from 1 to 9 units. A suitable connection is provided between each key and its associated cam plate, which may be in the form of a pin 32 mounted in each key and adapted to co-operate with a slot or notch 33 in a forwardly extending arm of the plate. For each 115 group of keys there is provided a segment frame comprising a pair of forwardly extending arms 34, loosely mounted upon a transverse shaft 35. Between each pair of arms 31 and supported at its ends by the latter is a rod 36 which normally rests in the open end of the graduated cam slots 31 of the series of cam plates 30 associated with the operating keys of a particular group.

120 Each of the segment frames is movable 125 with its related operating segment 37 mounted on the shaft 35 and adapted to differentially adjust item type carriers and to operate the totalizing devices. The segments 37 are nested while the segment frames extend trans- 130

versely of the machine and to transmit movement from the frames to the segments and suitable cross connections may be used and since this mechanism is not involved in the 5 present application it is not shown or described in detail herein. One form which may be used is illustrated in the parent application above identified.

As the operating key of a particular group 10 is depressed it will rock its associated cam plate 30 by means of the pin and slot connection 32, 33, and this cam plate, through its cam slot 31, will engage the rod 36 and rock the segment frame related to the key depressed 15 an amount depending upon the value of the cam slot. Rocking of the segment frame will serve to rock the related actuating segment 37 in a counter-clockwise direction (Fig. 1) about the shaft 35. Upon release of 20 the operated key after full depression, the parts described will return to their normal position.

The machine, as herein disclosed, is provided with a plurality of totalizers (two being shown) Figs. 1 and 3, which are adapted 25 to selectively receive and accumulate the several amounts entered into the machine. The machine is so constructed that both of the totalizers are out of engagement with the 30 actuating segments, but one of them is adapted to be normally rocked into engagement with the segments, at the beginning of the down-stroke of the keys, while at the end of the down-stroke or the beginning of the 35 return of the keys this totalizer is again disengaged from the actuating segments. Whenever it is desired to add an amount in the other totalizer, a clerk's or totalizer selecting key is operated and has the effect of causing 40 the engagement with the actuators of the second or selected totalizer and preventing the engagement of the first mentioned totalizer. Provision is further made for preventing the engagement of either of the totalizers, whenever 45 a special key of another character, such as one designating a special transaction, is depressed. The mechanism for accomplishing the above results will now be explained.

It will be noted that a pair of totalizer 50 frames 38_A and 38_B are provided, and the totalizers will be hereinafter designated as the "A" and "B" totalizers respectively. Each totalizer frame is provided with a pair of supporting hubs 39 which are adapted to co-operate 55 with a pair of studs 40, projecting from each of the pair of intermediate supporting frames 41 and 42. The totalizer frames 38_A and 38_B are each provided with a totalizer wheel supporting shaft 43_A and 43_B respectively on which are mounted a plurality 60 of totalizer wheels 441. Adjacent each of the wheels of the totalizer, and secured to the latter, is mounted a pinion 451 which is adapted, at times, to co-operate with the associated driving segments 37 for the purpose

of rotating the totalizer wheels to enter an item.

For the purpose of rocking the totalizers about their supporting studs 40 and in order to carry the pinions 451 into mesh with the 70 actuating segments 37, a rockable and slidable plate 44 is provided. This plate is pivoted at 45 to the upper end of an arm 46 secured to a shaft 47. The rearward end of the plate is provided with a forked projection 48, adapted 75 to co-operate with a pin 49 carried by a rock lever 50, pivoted at 51 to the intermediate frame 41. A downwardly projecting extension of the rock lever carries a suitable pin or roller adapted to co-operate with the race-way of a box cam 52 secured to the main operating shaft 29. This cam is so formed that during the early part of the operation of the machine the rock arm 50 will be lowered, while toward the beginning of the return 80 stroke of the keys and the coupler the arm will be elevated to its normal position again. It will be obvious that rocking of the arm 50 will impart a rocking movement to the plate 44, first in a downward or counter-clockwise 85 direction and then upwardly in a clockwise direction. The upper rear corner of the plate 44 is provided with a square notch 53 which provides a rearwardly extending finger 54, which is adapted to normally engage the upper surface of the "A" totalizer wheel supporting shaft 43_A. Similarly, toward the forward upper edge of the plate, a square notch 55 is provided and forms a finger 56 adapted to be brought over the upper surface 90 of the "B" totalizer wheel supporting shaft 43_B.

It will be noted that when the plate is in the position shown in Fig. 1 and the machine is operated to cause the arm 50 and the plate 44 to be rocked downwardly, the finger 54 will engage the "A" totalizer wheel supporting shaft and rock the pinions 451, carried by the latter, into engagement with the teeth of the actuating segments 37. However, if the plate 44 is shifted, in a manner to be described, slightly to the right of the position shown in Fig. 1, the finger 54 will be carried clear of the "A" totalizer supporting shaft 43_A, while the forward finger 56 will be carried over the "B" totalizer supporting shaft 43_B, so that upon a subsequent downward rocking of the plate 44 about its pivot 45 the "B" totalizer pinions 451 will be meshed with the actuating segments 37 while the "A" totalizer pinions will not be engaged. Movement of the plate 44 to bring about the reversal of action of the fingers 54 and 56, is produced by shifting of the pivot 45 through rocking of the shaft 47 and the arm 46 against the action 105 of a spring 57 which normally maintains the parts in the position shown. Rocking of the shaft 47 is brought about by the operation of a "B" clerk's or totalizer selecting key 58_B similar to the amount keys and which carries 110

a pin 59 adapted to engage a cam surface 60 on a cam shoe 61 secured to the shaft 47. It will be noted that the cam shoe is so shaped that the initial depression of the key 58_B will serve to rock the shaft 47 and hence move the plate 44, to cause the selection of the "B" totalizer and the disablement of the "A" totalizer.

It has been mentioned that, when desired, the totalizer engaging mechanism may be completely disabled, so that neither totalizer will be carried into engagement with the actuating segments. This result is brought about by the use of certain of the special transaction keys 62. Each of these keys is provided with a pin similar to pin 59 which is adapted to co-operate with a cam shoe 63, also secured to the shaft 47. It will be noted that the cam formation of the shoe 63 is steeper than that of the shoe 61, so that operation of one of the special transaction keys 62 will cause a further movement of the shaft 47 and arm 46 than was caused by the clerk's or totalizer selecting key 58_B. This movement of the arm 46 under the influence of one of the keys 62, which is prior to any rotation of the shaft 29, will shift the plate 44 forwardly until its forked end 48 is disengaged from the pin 49. It will be obvious, therefore, that subsequent rocking of the arm 50 will have no effect upon the plate 44 and will not cause the engagement of the "B" totalizer even though the finger 56 will extend over its totalizer wheel supporting shaft 43_B.

Suitable mechanism is provided and associated with the plate for preventing the rocking of one or the other, or both, of the totalizers, when they are not intended to be engaged with the actuating segments. The means, illustrated, for accomplishing this purpose, as best shown in Fig. 2, comprises a detent plate 64 pivoted at 65 to the intermediate supporting frame 41. A suitable connection is provided between the plate 44 and the detent plate 64, which, as shown, takes the form of a pin 66 extending from the plate 44 into co-operation with a slot 67 in the detent plate 64. In the normal position of the parts a detaining surface 68 of the detent plate is in engagement with the under surface of the "B" totalizer wheel supporting shaft 43_B, and thereby effectively prevents the rocking of the forward totalizer frame during a normal operation of the machine. However, when the plate 44 is shifted forwardly, under the influence of a clerk's or totalizer selecting key 58_B, therefore 68 will be carried away from the shaft 43_B while, at the same time, a surface 69 of the plate 64 will be carried under the "A" totalizer wheel supporting shaft 43_A. Consequently, upon an operation of the machine in which the clerk's key 58_B has been depressed, the "A" totalizer will be positively locked against rocking into engagement with the actuating segments,

while rocking of the "B" totalizer frame will be permitted. When the plate 64 is given the additional forward movement, under the influence of a special transaction key 62, a surface 70 (Fig. 1) of the plate 44 will be carried over a stud 71 extending from the side of the intermediate supporting frame 41. During an operation of the machine, therefore, in which a key 62 has been operated, the pin and slot connection 48, 49 will not only be disabled, but rocking of the plate 44 will be positively prevented by the engagement of surface 70 with the pin 71 and the lower edges of the square notches 53 and 55 with the under surfaces of the pair of shaft 43_A and 43_B respectively.

It will be obvious that by varying the normal relationship between the pair of shafts 43_A and 43_B and the engaging fingers 54 and 56 of the plate 44, as well as the detaining surfaces 68 and 69 of the detent plate 64, the foregoing totalizer engaging mechanism may be readily modified to adapt it for use in a variety of systems of accounting.

While the form of mechanism herein described is admirably adapted to fulfill the objects primarily stated, it is to be understood that it is not intended to confine the invention to the one form of embodiment herein shown, since it may be embodied in various forms, all coming within the scope of the claims which follow:—

What is claimed is:—

1. In a machine of the class described, a plurality of totalizers, actuators therefor, a main operating mechanism, a member operated by said main operating mechanism for selectively causing the engagement of said totalizers with the actuators, a key controlling said member to select a totalizer for engagement with the actuators, and one or more keys for controlling said member to prevent the engagement of any totalizer with the actuators.

2. In a machine of the class described, a plurality of totalizers, actuators therefor, a main operating shaft, a member operated by said shaft for selectively engaging one of the totalizers with the actuators, manipulative means for selecting the totalizer to be engaged with the actuators by said member, and keys for shifting said member to prevent the engagement of the selected totalizer.

3. In a machine of the class described, a plurality of totalizers, actuators therefor, an operating shaft, a pivoted and slid able member adapted to be rocked by said shaft for selectively engaging a totalizer with the actuators, a key for controlling the shifting of the pivotal point of said member for selecting a totalizer to be engaged with the actuators, and one or more keys for shifting the pivotal point of said member a different extent to prevent the engagement of the selected totalizer with the actuators.

4. In a machine of the class described, a plurality of totalizers, actuators therefor, means for engaging the totalizers selectively with the actuators, a plurality of keys arranged in groups, a member common to said keys of a plurality of the groups to control said totalizer engaging means, connections from a key of one of said groups to said common member for selecting a totalizer to be engaged with the actuators, and connections from the keys of another of said groups for controlling said common member to prevent the engagement of the selected totalizer. 5
5. In a machine of the class described, a plurality of totalizers, actuators therefor, a main operating shaft, a member normally operatively connected with said shaft for selectively engaging a totalizer with the actuators, means for shifting said member differentially, keys for controlling said shifting means, and connections between said member and said totalizers whereby in certain positions of said member one or another of said totalizers will be selected for engagement with the actuators, while in another position of said member none of the totalizers will be conditioned for engagement with the actuators. 10
6. In a machine of the class described, a plurality of totalizers, actuators therefor, a main operating mechanism, a member operated by said main operating mechanism for selectively causing the engagement of said totalizers with the actuators, manipulative means for controlling said member to select a totalizer for engagement with the actuators, manipulative devices for controlling said member to prevent the conditioning of any totalizer for engagement with the actuators, and means controlled by said member for preventing the engagement of the unselected totalizers with the actuators. 15
7. In a machine of the class described, a plurality of totalizers, actuators therefor, a main operating shaft, a member operated by said shaft for selectively engaging one of the totalizers with the actuators, manipulative means for selecting the totalizer to be engaged with the actuators by said member, keys for shifting said member to prevent the conditioning of any totalizer for engagement with the actuators, and means controlled by said member for preventing the engagement of the unselected totalizers with the actuators. 20
8. In a machine of the class described, a plurality of totalizers, actuators therefor, an operating shaft, a pivoted member for selectively engaging a totalizer with the actuators, manipulative means for shifting the pivotal point of said member for selecting a totalizer to be engaged with the actuators, manipulative devices for shifting the pivotal point of said member a different extent to prevent the conditioning of any totalizer for engage- 25
- ment with the actuators, and means controlled by said member for preventing the engagement of the unselected totalizers with the actuators. 30
9. In a machine of the class described, a plurality of totalizers, actuators therefor, means for engaging the totalizers selectively with the actuators, a plurality of keys arranged in groups, means common to the keys of a plurality of the groups to control said totalizer engaging means, connections from a key of one of said groups to said common means for selecting a totalizer to be engaged with the actuators, connections from the keys of another of said groups for controlling said common means to prevent the engagement of the selected totalizer, and means controlled by said engaging means for preventing the engagement of the unselected totalizers with the actuators. 35
10. In a machine of the class described, a plurality of totalizers, actuators therefor, a main operating shaft, a member normally operatively connected with said shaft for selectively engaging a totalizer with the actuators, means for shifting said member differentially, keys for controlling said shifting means, connections between said member and said totalizers whereby in certain positions of said member one or another of said totalizers will be conditioned for engagement with the actuators while in another position of said member none of the totalizers will be conditioned for engagement with the actuators, and means controlled by said member for preventing the engagement of the unselected totalizers with the actuators. 40
11. In a machine of the class described, a plurality of totalizers, supporting shafts therefor, actuators for said totalizers, a main operating mechanism a pivoted and slid able member movable to a plurality of positions by shifting its pivot, keys for controlling the shifting of the pivot of said member, and means formed on said member for selectively engaging one or another of said totalizer supporting shafts for engaging a selected totalizer with the actuators in certain positions of said member, said means being rendered ineffective with respect to all of said shafts thereby preventing engagement of the totalizers with the actuators when said member is shifted to another position. 45
12. In a machine of the class described, a plurality of totalizers, supporting shafts therefor, actuators for said totalizers, a main operating mechanism, a pivoted and slid able member movable to a plurality of positions by shifting its pivot, keys for controlling the shifting of the pivot of said member, means formed on said member for selectively engaging one or another of said totalizer supporting shafts for engaging a selected totalizer with the actuators in certain positions of said member, said means being rendered in- 50

effective to condition any totalizer for engagement with the actuators in another position of said member, and means controlled by said member for preventing the engagement of the unselected totalizers with the actuators.

13. In a machine of the class described, a plurality of totalizers, supporting shafts therefor, actuators for said totalizers, a main operating mechanism, a member movable to select one or another of said totalizers for engagement with the actuators, connections from said operating mechanism to said member to engage the selected totalizer with the actuators, and means for disabling said connections by movement of said member, thereby preventing the engagement of any totalizer with the actuators.

14. In a machine of the class described, a plurality of totalizers, supporting shafts therefor, actuators for said totalizers, a main operating mechanism, a member movable to select one or another of said totalizers for engagement with the actuators, connections from said operating mechanism to said member to engage the selected totalizer with the actuators, means for disabling said connections by movement of said member, thereby preventing the engagement of any totalizer with the actuators, and means controlled by said member for preventing the engagement of the unselected totalizers with the actuators.

15. In a machine of the class described, a plurality of operating keys, a plurality of totalizers, actuators driven by said operating keys, means for selectively engaging a totalizer with the actuators, said means including a differentially movable member, connections from one of said keys for moving said member to select a totalizer for engagement with the actuators, and connections from other of said keys for moving said member to prevent the engagement of any totalizer with the actuators.

16. In a machine of the class described, a plurality of operating keys, a plurality of totalizers, actuators driven by said operating keys, means for selectively engaging a totalizer with the actuators, said means including a differentially movable member, connections from one of said keys for moving said member to select a totalizer for engagement with the actuators, connections from other of said keys for moving said member to prevent the engagement of any totalizer with the actuators, and means controlled by said member for preventing the engagement of the unselected totalizers with the actuators.

17. In a machine of the class described, a totalizer, actuators therefor, a main operating mechanism, a pivoted and slidable totalizer control member, connections from said operating mechanism for rocking said member to engage the totalizer with the actuators,

and means for shifting said member by movement of its pivot to disable said connections.

18. In a machine of the class described, a totalizer, actuators therefor, a main operating mechanism, a pivoted and slidable totalizer control member, connections from said operating mechanism for rocking said member to engage the totalizer with the actuators, means for shifting said member by movement of its pivot to disable said connections, and means controlled by said member for preventing the engagement of said totalizer with the actuators when said connections are disabled.

19. In a machine of the class described, a totalizer, actuators therefor, item entering means for controlling the actuators, a pivoted and slidable totalizer control member, means for rocking said member to engage the totalizer with the actuators, a plurality of special keys, and means controlled by said special keys for shifting said member by movement of its pivot to disable said means for rocking the member.

20. In a machine of the class described, a totalizer, actuators therefor, item entering means for controlling the actuators, a pivoted and slidable totalizer control member, means for rocking said member to engage the totalizer with the actuators, a plurality of special keys, means controlled by said special keys for shifting said member by movement of its pivot to disable said means for rocking the member, and means controlled by said member for preventing the engagement of said totalizer with the actuators when one of said special keys is operated.

21. In a machine of the class described, a totalizer, actuators therefor, item entering means for controlling the actuators, a differentially movable totalizer control member, means for operating said member upon each operation of the machine, a plurality of keys, connections from one of said keys for shifting said member to cause the engagement of the totalizer with the actuators upon an operation of the machine, and connections from another of said keys for shifting said member to prevent the engagement of the totalizer with the actuators.

22. In a machine of the class described, a plurality of totalizers, actuators therefor, an operating shaft, a shiftable member adapted to be rocked by said shaft for selectively engaging a totalizer with the actuators, a key for controlling shifting of said member for selecting a totalizer to be engaged with the actuators, and a plurality of keys for shifting said member a different extent to prevent the engagement of the selected totalizer with the actuators.

23. In a machine of the class described, a plurality of totalizers, actuators, therefor, an operating shaft, a shiftable member adapted to be rocked by said shaft for selectively en-

- gaging a totalizer with the actuators, a key for controlling shifting of said member for selecting a totalizer to be engaged with the actuators, and a plurality of keys for shifting 5 said member a different extent to disconnect said member from the operating shaft and prevent the engagement of the selected totalizer with the actuators.
24. In a machine of the class described, a 10 plurality of totalizers, actuators therefor, an operating shaft, a shiftable member operated by the operating shaft for selectively engaging a totalizer with the actuators, manipulative means for shifting said member for 15 selecting a totalizer to be engaged with the actuators, manipulative devices for shifting said member a different extent to disengage said member from the operating shaft and prevent the selection of any totalizer for 20 engagement with the actuators, and means controlled by said member for preventing the engagement of the unselected totalizers with the actuators.
25. In a machine of the class described, a 25 shaft, a totalizer mounted on said shaft, actuators therefor, a main operating mechanism, a pivoted and slidable totalizer control member slidably engaging said shaft, connections from said operating mechanism for 30 rocking said member to engage the totalizer with the actuators, and means for shifting said member to disable said connections.
26. In a machine of the class described, a 35 shaft, a totalizer mounted on said shaft, actuators therefor, a main operating mechanism, a pivoted and slidable totalizer control member slidably engaging said shaft, connections from said operating mechanism for rocking said member to engage the totalizer with the 40 actuators, means for shifting said member to disable said connections, and means controlled by said member for preventing the engagement of said totalizer with the actuators when said connections are disabled.
27. In a machine of the class described, a 45 shaft, a totalizer mounted on said shaft, actuators therefor, item entering means for controlling the actuators, a pivoted and slid- 50 able totalizer control member slidably en- gaging said shaft, means for rocking said member to engage the totalizer with the actuators, a plurality of special keys, and means controlled by said special keys for shifting said member to disable said means for rock- 55 ing the member.
28. In a machine of the class described, a shaft, a totalizer mounted on said shaft, actuators therefor, item entering means for controlling the actuators, a pivoted and slid- 60 able totalizer control member slidably en- gaging said shaft, means for rocking said member to engage the totalizer with the actuators, a plurality of special keys, means controlled by said special keys for shifting said member to 65 disable said means for rocking the member,
- and means controlled by said member for preventing the engagement of said totalizer with the actuators when one of said special keys is operated.
29. In a machine of the class described, a 70 plurality of totalizers, a main operating mechanism, a member movable to select one or another of said totalizers for engagement with the actuators, connections from said operating mechanism to said member to engage 75 the selected totalizer with the actuators, means for disabling said connections by movement of said member and a fixed stop for said member preventing movement thereof in a given direction when disconnected 80 from the main operating mechanism.
30. In a machine of the class described, a plurality of totalizers, actuators therefor, a main operating mechanism, a control member having two different movements one for 85 selecting a totalizer for actuation and the other for engaging the selected totalizer with the actuators, connections from said operating mechanism for causing engagement of a selected totalizer with the actuators and 90 means for moving said member to disable said connections.
31. In a machine of the class described, a totalizer, actuators therefor, a main operating mechanism, a pivoted and slid- 95 able totalizer control member, connections from said operating mechanism for rocking said member to engage the totalizer with the actuators, means for sliding said member by movement of its pivotal connection to disconnect 100 said member from the operating mechanism, and additional means for sliding said member to connect said member with the operating means.
